UNITED STATES PATENT OFFICE.

FRANK E. FOOR, OF INDIANAPOLIS, INDIANA.

COMBINATION-TOOL.

1,026,347.

Specification of Letters Patent.

Patented May 14, 1912.

Application filed April 13, 1911. Serial No. 620,745.

To all whom it may concern:

Be it known that I, FRANK E. FOOR, a citizen of the United States, residing at Indianapolis, in the county of Marion and 5 State of Indiana, have invented certain new and useful Improvements in Combination-Tools, of which the following is a specification.

This invention is for lifting heavy loads 10 such as vehicles and machinery, for pulling posts, stumps, and the like, for holding the ends of severed wires and bringing them together for splicing, for stretching fence wires, and as a vise or clamp for the usual 15 purposes of such appliances.

The object of the invention is to provide a strong, simple, and inexpensive tool for the above uses, which will be positive and sure in its adjustments, and which can be 20 assembled and dismantled readily to permit the separate use of its parts.

I accomplish the objects of the invention by the mechanism illustrated in the accompanying drawing, in which—

25 Figure 1 is a view in side elevation and partial section of my improved tool. Fig. 2 is a detail of same showing the parts in full which are shown in section in Fig. 1. Fig. 3 is a cross section on the line 3—3 of Fig. 2. Fig. 4 is a view in side elevation and Fig. 5 is a plan view of the spring bar for controlling the position of the pawl in the upper runner and Fig. 6 is a plan view of the base plate of the tool.

30 Like characters of reference indicate like parts throughout the several views of the drawings.

7 is the main or standard bar of my tool having ratchet teeth 6 along one edge and 40 8 a removable base-plate which is preferably of the shape of a shoe sole as shown in Fig. 6, to adapt that part of the tool for use as a last in repairing shoes. The sole-plate has a lug with a socket therein to receive the end of the standard 7, the standard being removably secured in the socket by a cotter-pin 9 to permit it to be taken off when the tool is used as a wire stretcher. To the opposite end of the standard-bar 7 45 50 is a handle 10, having a socket to receive the upper end of the standard-bar. The latter is secured in the socket by a cotter-pin 11.

12 is a movable hook-head, preferably of 55 malleable iron, formed with two parallel

side plates between which the standard-bar 7 is inserted as shown in the drawings.

13 is an operating-lever having a handle at its outer end and having its other end turned approximately at right angles and 60 provided with an integral journal-pin 14. The pin is inserted through suitable openings in the two plates of the head 12. It has two opposite lugs 15 which pass through suitable enlargements of the pin-opening 65 in the plate next the lever when the lever is suitably elevated and lock the pin against removal when the lever is lowered after such insertion. The lever 13 has a second pin 17 on the same side as and parallel with 70 the pin 14. The plates of the head 12 have arcuate slots 18 concentric with openings for pin 14 through which pin 17 passes, and on the outer pin 17 one end of a pitman 19 is mounted. The pitman 18 has an eye at 75 its lower end and a laterally projecting arm 20 with a lug or pin 21 on its upper face.

A lower runner 22 is recessed to receive the lower end of the pitman 19 and arm 20, a suitable socket being formed to receive 80 the rounded end of the pitman. A spring 23, retained in position by pin 21, presses down against the arm 20 with a resulting tendency of moving or swinging the body of runner 22 upwardly around the lower 85 end of the pitman as a pivot. A bite-member 24 of hardened steel, is inserted in the runner to contact with the standard 7 and the action of the spring 23 keeps the bite-member in contact with the bar 7. 90

25 is a second or upper runner of the same general construction as the lower runner 22, but in reversed position. It has a pitman 26 similar to pitman 19, with an arm 20 and spring 23 for the same purpose. The upper end of pitman 26 has its bearing in a socket in an extension 27 of the hook-head 12. The essential difference in construction between the upper and lower runners is that instead of a bite-member 24, a pawl 28 is mounted in a suitable cavity in the runner, on a pivot-bolt 29, and the free pointed end of the pawl is adapted to engage with the ratchet teeth of the standard-bar 7. This change is 100 to insure stronger and more positive engagement or hold between the bar 7 and runner 25 than is possible with a bite-member 24 as in the lower runner 22.

To hold the pawl 28 in such yielding engagement with the bar 7 as will permit it 110

to ride over the teeth I provide a spring-bar 30, one end of which is bent inwardly and is inserted in the pawl, and the other end is bent outwardly and passes out of the hollow runner through a slot 31 and is continued sufficiently to form a handle 32 for manipulation. This bar is resilient, the means here employed being a coil 33. The slot 31 terminates with notches 34 and 35. When the handle 32 is in notch 34 the pawl 28 will be held out of engagement with the notches of bar 7, which is the position when the runner 25 is to be lowered; but when the handle 32 is in notch 35 the pawl is held 15 yieldingly in contact with ratchet teeth 6 of bar 7.

The handle 10 at the upper end of standard-bar 7 is provided with a vise or jaw extension 40 to coöperate with the corresponding jaw formed by the extension 27 of head 12. As the handle 10 and head 12 are preferably made out of malleable iron which is too soft for good vise jaws, I provide dove tailed channels in the two jaws and drive 25 correspondingly shaped bearing blocks 42 of hardened steel therein, to take the wear. This is an important feature in a practical tool.

Extending longitudinally of the bar 7 across the handle-piece is a toothed bar 44 having an overhanging flange, and pivotally secured to the handle-piece is a serrated cam-segment lever 45, to make clamping engagement with a wire placed between the bar 44 and cam-lever 45.

The head 12 has the toothed extension 47 coöperating with a serrated cam-lever 48 pivoted adjacent to the extension 47. These

parts are to hold the ends of a wire being stretched by the stretcher mechanism, and holds them taut during the operation of twisting said ends together.

Having thus fully described my invention, what I claim as new and wish to secure by Letters Patent, is—

1. In a lifting-jack having a toothed standard-bar and having a runner slidingly mounted thereon said runner having a slotted plate, and said jack having a pawl pivoted to the runner and adapted to engage the teeth of the standard-bar, a spring-bar attached at one end to the pawl and having its other end bent and extending through said slot in the plate of the runner, and said slot having notches to hold given adjustments of the bar.

2. A toothed standard-bar, a hollow runner slidingly mounted on the bar having a slotted plate with end notches, a pawl mounted in the runner and adapted to engage the teeth of the bar, and a spring-bar having one end bent and attached to the pawl and the other end bent and passed out of the runner-plate through its slot and adapted to engage the notches in the slot, said spring-bar having a coil between its ends to give it resiliency.

In witness whereof, I, have hereunto set my hand and seal at Indianapolis, Indiana, this, 20th day of October, A. D. one thousand nine hundred and ten.

FRANK E. FOOR. [L.S.]
